UNITED STATES PATENT OFFICE

153,677

DESIGN FOR A COMBINED COMPACT KEY
AND MONEY CLIP OR THE LIKE

George E. Georganta, Muskegon, Mich.

Application June 27, 1947, Serial No. 139,949

Term of patent 14 years

(Cl. D17—14)

To all whom it may concern:

Be it known that George E. Georganta, a citizen of the United States of America, residing at the city of Muskegon, in the county of Muskegon and State of Michigan, has invented a new, original, and ornamental Design for a Combined Compact Key and Money Clip or the like, of which the following is a specification, reference being had to the accompanying drawing, forming part thereof.

Fig. 1 is a perspective view of a combined compact key and money clip or the like, showing my new design, the outlines of two keys shown in broken lines are for illustrative purposes only.

Fig. 2 is a side elevational view thereof, the keys shown in broken lines in Fig. 1 having been omitted for convenience of illustration.

I claim:

The ornamental design for a combined compact key and money clip or the like, substantially as shown and described.

GEORGE E. GEORGANTA.
